W. E. DIEGEL

CIGARETTE HOLDER AND ASH TRAY

Filed July 27, 1925

FIG. 2.

FIG. 3.

Inventor

Wilfrid E. Diegel.

By Adam E. Fisher.

Attorney
P.S.

UNITED STATES PATENT OFFICE.

WILFRID E. DIEGEL, OF RIVER ROUGE, MICHIGAN.

CIGARETTE HOLDER AND ASH TRAY.

Application filed July 27, 1925. Serial No. 46,296.

This invention is a cigarette holder and ash tray combined. The main object of the invention is to provide a convenient and practicable cigarette holder with an ash tray extension therefor. Another object is to provide a combined holder and tray in a telescoping form, whereby, when not in use, the mouthpiece may be reversed in the end of the ash tray, so as to materially shorten the total length of the two elements and adapt the device for carrying in the vest pocket.

In the drawing—

Figure 1 is a plan view of the device in extended relation;

15 Figure 2 is a plan view showing the device with the mouthpiece reversed and telescoped into the ash tray;

Figure 3 is a side elevation showing a cigarette in place therein;

20 Figure 4 is an end view of the mouthpiece;

Figure 5 is an end view of the ash tray;

Figure 6 is a longitudinal horizontal section of the assembly as shown in Figure 1.

25 This invention comprises a conventional mouthpiece 1, formed with an exterior, annular offset or shoulder 2 at that end of the mouthpiece intended for engaging the cigarette 3. Thus a reduced stem 9 is provided at this end. An ash tray 4 is provided, the same being semi-tubular or trough-like in formation, and of a length to accommodate the standard sized cigarette 3. The outer end of this tray is closed as shown at 5, and a hole 6 may be punched at this end, to facilitate attaching the device to a watch chain or the like. The opposite end of the tray 4 is provided with a ferrule 7 which is

thickened inwardly relative to the shell of the tray 4 so as to form a shoulder 10 corresponding to the shoulder 2 of the mouthpiece. By this arrangement the reduced stem 9 of the mouthpiece 1 is adapted to frictionally engage the ferrule 7 and may be readily inserted therein from either direction, according as the device is to be extended for use as shown in Figure 3, or is to be shortened for carrying in the pocket, as shown in Figure 2. The edges of the tray 4 may be scalloped as shown at 8 for the sake of ornamentation. This device both serves to hold the cigarette, and also to prevent ashes from falling onto the floor.

While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

I claim:

In a device of the kind described, the combination of a cigarette holder and ash-tray, the ash-tray being trough-like and having one end closed and being provided with a ferrule at the opposite end, the said ferrule being thickened inwardly relative to the shell of the said tray so as to form a shoulder; and a mouthpiece having a reduced stem adapted to frictionally engage the said ferrule from either side thereof.

In testimony whereof I affix my signature.

WILFRID E. DIEGEL.
